BOBBIN ARBOR

William Elias Detwiler Welch, Rome, Ga., assignor, by mesne assignments, to Celanese Corporation of America, a corporation of Delaware

Application June 13, 1945, Serial No. 599,266

6 Claims. (Cl. 242—72)

1 This invention relates to arbors for the support and rotation of cylindrical bobbins, and has for its object the provision of an improved arbor particularly adapted to permit ready reception and removal of a bobbin and at the same time adapted to firmly hold the bobbin in operative position.

The arbor of the invention may be used for the support and rotation of a cylindrical bobbin in various thread-winding, unwinding, twisting and similar operations, but is especially adapted for unwinding rayon thread from packages on bobbins as described in the United States patent of Cooper No. 2,331,454. In accordance with the heretofore customary practice, the thread package is wound on a cylindrical metal bobbin, usually perforated, and the bobbin is carried on a rotateably mounted arbor. This arbor has heretofore been made of wood with a blank metal disc on one end and fitted at both ends with bearing or gudgeon pins. Three equally spaced longitudinal arms radiate from the body of the arbor, and strips of felt are secured in grooves in the longitudinal edges of these arms. When new, this arbor is forced into the bobbin and has a relatively snug grip to prevent slippage. However, as the felt strips wear, slippage increases and the strips must be frequently replaced. Moreover, due to fouling of the felt strips or the use of undersized bobbins, the arbor frequently sticks in the bobbin, and is removed by striking one end of the arbor. A lead washer is usually mounted on this striking end of the arbor for balance only, and in many instances this washer is knocked off by the striking or hammering of the arbor to remove it from the bobbin. While special bumpers are provided for striking the arbors, operators often strike the arbor against any protruding machinery part to remove it from the bobbin, and this frequently causes damage to the machinery part. With this type of arbor, no adjustment of its effective peripheral diameter is possible except by varying the width of the felt strip, and this is neither satisfactory nor practical. Consequently, the use of these arbors entails a constant and high maintenance cost in addition to frequent periodic replacements.

The arbor of the invention is characterized by its ready and convenient insertion into and removal from a bobbin without damage to the arbor and without the attendant difficulties hereinbefore recited. Generally speaking, the arbor of the invention has floating or pivoted arms which are expanded or contracted by means of an operating disc turned clockwise or counterclockwise.

2 Thus, the arbor comprises a generally cylindrical body member, conveniently made of wood, and having a plurality of circumferentially spaced longitudinal peripheral grooves. A radially extending arm is positioned in each groove and is pivotally secured at one end to the body member, the other or free end of each arm being capable of radial movement about its pivot. Associated with such free ends of the arms is means for simultaneously imparting a limited predetermined radial movement to the arms, whereby the arms may be protracted and retracted to increase or decrease, respectively, the effective peripheral diameter of the arbor. Preferably, this means comprises a disc mounted to turn about the longitudinal axis of the body member and having a plurality of eccentric slots, circumferentially spaced like the arms, into which extend pins protruding from the free ends of the arms. Turning of the disc simultaneously imparts a similar limited radial movement to each of the pivoted arms, whereby the arms are retracted and protracted to decrease and increase the effective peripheral diameter of the arbor for respectively (1) insertion into and removal from and (2) operatively holding a bobbin. These and other novel features of the invention will be best understood from the following description taken in conjunction with the accompanying drawings, in which

30 Fig. 1 is a longitudinal cross section of the arbor of the invention, with a spin bobbin thereon.

Figs. 2 and 3 are transverse sections on the line 35 2—2 of Fig. 1, with the longitudinal arms in their protracted and retracted positions, respectively.

Fig. 4 is an end view of the operating end of the arbor and bobbin shown in Fig. 1.

Fig. 5 is a transverse section on the line 40 5—5 of Fig. 1.

Fig. 6 is a detail view of the end washer for the body member of the arbor, and

Fig. 7 is an elevation of a thread unwinding apparatus with which the arbor may be advantageously used.

The arbor of the invention has a base end and an operating end, being the left and right hand ends, respectively, as viewed in Fig. 1.

The body member 10 of the arbor is generally 50 cylindrical and is conveniently made of wood, although it may be made of any other suitable material. Circumferentially spaced about its periphery, the body member has three grooves 11 extending throughout the longitudinal length 55 of the member. An arm 12 is positioned in each

groove, and each arm is pivoted at the base end of the body member. Conveniently, the base end of the body member may have an enlarged hub or spider 13 for facilitating the insertion of a pivot pin 14 through the end of each arm 12. The arms are loosely fitted in their respective grooves, so that their free ends are capable of a certain amount of radial movement about the pivot pins 14.

A generally circular disc 15 is operatively mounted at the operating end of the body member 10, adjacent the free ends of the arms 12. The disc 15 may conveniently be mounted to turn freely on a bearing or gudgeon pin 16 positioned in the longitudinal axis of the body member 10 and appropriately secured thereto, as for example by being inserted a suitable distance in the center of the operating end of the member 10 (Fig. 1). As illustrated in the drawings, the pin 16 has an enlarged hub 17 on which the disc 15 is rotatably mounted and an outside restraining washer 18, which also serves as a bearing washer for the bearing end of the pin 16. A washer 19 is secured by screws 20 or the like to the end of the member 10, and the disc 15 is positioned between the washers 18 and 19 and turns freely on the hub 17.

The disc 15 may advantageously be made of hard fiber, and has three eccentric slots 21, circumferentially spaced to conform with the circumferentially spaced arms 12. It will be understood that the arbor may be provided with more than three arms, equally spaced about the periphery of the body member 10, and the disc 15 will have a corresponding number of similarly spaced eccentric slots 21. The free ends of the arms 12 are provided with protruding pins 22 which extend into the corresponding slots 21 of the disc 15. The disc 15 has cut-outs or indentations 23 and a serrated peripheral edge to permit it to be readily grasped and turned by the hand of the operator.

The arms 12 are preferably made of wood and their outer edges have longitudinal slots into which are tightly fitted resilient strips or cushions 24, such for example as strips of synthetic rubber, having ample traction and resiliency. The base end of the member 10 is covered by a disc 25, preferably of hard fiber, fastened to the member 10 by screws 26 or the like. The disc 25 serves as a hand hold as well as stop for the bobbin. A bearing or gudgeon pin 27 is inserted a suitable distance in the center of the base end of the member 10.

The eccentric slots 21 and cooperating pins 22 may be considered as cams and cam-followers, respectively. When the pins are at the rearward ends of the slots, as indicated in Fig. 4, the arms 12 are in their protracted positions, as indicated in Fig. 2. Turning the disc 15 counter-clockwise, as viewed in Fig. 4, moves the pin 22 to the forward ends of the slots 21 and radially withdraws the arms 12 to their retracted positions, as indicated in Fig. 3. Most of the radial movement of the arms is effected as their pins move through the forward half of the slots, and the movement of the pins through the rearward half of the slots is in the nature of a locking action, as will be seen from an inspection of the configuration of the slots in Fig. 4. In other words, the forward half of each slot 21 is entirely eccentric, while the rearward half of the slot is practically concentric, with respect to the longitudinal axis of the arbor.

In the operation of the arbor, the disc 15

is turned to position the pins 22 at the forward ends of the slots 21, and the arms 12 are retracted and the arbor has its minimum effective peripheral diameter. The arbor is then inserted in a bobbin 28, such for example as the common perforated metal spin bobbin. The disc 15 is then manually turned until the pins 22 occupy the rearward ends of the slots 21. The first half of this turning movement protracts the arms 12 until the arbor has its maximum effective peripheral diameter, and the second half of the turning movement locks the arms in their protracted positions. The resilient strips 24 press against the interior of the bobbin and securely hold it on the arbor. Where the bobbin carries a package of thread 29 to be unwound, the arbor of the invention, with the bobbin and thread package secured thereon, may be mounted with its gudgeon pins 16 and 27 in the slots 30 of the upright supports 31, and the thread unwound at a uniform speed by engagement of the peripheral surface of the package with a uniformly driven endless belt 32, as particularly described in the aforementioned Patent No. 2,331,454. The base disc 25 and the bearing washer 18 protect the bobbin 28 from damage on its ends by scraping on the sides of the supports 31. Heretofore there has been no such protection for the ends of the bobbin, and they have consequently suffered considerable damage.

The arbor of the invention is a unitary structure, light in weight, with no parts likely to be fouled by stray thread. It is easily handled, and can be inserted in and removed from a spin bobbin in less time than is now possible with the heretofore customary types of arbors. The arbor adjusts itself to various diameters of spin bobbins and at the same time exerts a uniform inside tension on the bobbin, preventing slippage and further placing a more uniform tension on the thread being unwound, twisted or the like. No friction is exerted on any parts of the bobbin during the insertion and removal of the arbor, but when the disc is turned the bobbin is firmly secured to the arbor. Only a small turn of the disc, for example less than an inch, locks the arbor inside the bobbin. The fulcrum action of the disc on the arms is of such a ratio that the arms may be locked or unlocked with a light pressure of one finger. Narrower strips of resilient material are possible with the arbor of the invention, as contrasted with the thick strips of felt required with the former type of arbor. This permits the use of synthetic rubber, which does not foul as does felt, and moreover is not deleteriously affected by oil as felt is. This ability to use thin strips of synthetic rubber, or the like, rather than thick strips of felt, is a distinct advantage of the arbor of the invention.

While the invention has been particularly described and illustrated in connection with a cylindrical metal bobbin, it is equally applicable to other types of bobbins and similar supports for yarn packages. For example, a rolled up sheet of Celluloid (or similar resilient material) inserted in the central opening of an otherwise unsupported annular cake of rayon (or the like) may be distended by inserting and locking the arbor of the invention within the Celluloid sheet. The thus distended Celluloid sheet is in effect a bobbin operatively mounted on the arbor of the invention.

I claim:

1. A bobbin arbor comprising a generally cylindrical body member having a plurality of cir-

cumferentially spaced grooves extending throughout the length of the member, a radially extending arm positioned in each of said grooves and pivotally secured at one end to the body member, a pin extending from the other and free end of each arm, a disc operatively secured to the body member to turn about the longitudinal axis thereof and provided with slots cooperating with said pins for simultaneously imparting a limited radial movement to the free ends of said arms.

2. A bobbin arbor comprising a generally cylindrical body member having a plurality of circumferentially spaced longitudinally extending peripheral grooves, a radially extending arm positioned in each of said grooves, one end of each of said arms being pivoted to the base end of said member and the other end of the arm having a pin protruding therefrom and being capable of radial movement about its pivot, and a disc operatively associated with the other end of said member and adapted to be turned about the longitudinal axis of the member, said disc having a plurality of eccentric slots circumferentially spaced like said arms and into which extend said pins protruding from the adjacent ends of said arms whereby turning of the disc simultaneously protracts or retracts said arms.

3. A bobbin arbor comprising a generally cylindrical body member having a plurality of circumferentially spaced longitudinally extending peripheral grooves, a radially extending arm positioned in each of said grooves, one end of each of said arms being pivoted to the base end of said member and the other end of the arm being capable of radial movement about its pivot, a pin protruding from said other end of each arm, a gudgeon pin centrally mounted in the other end of said member, a disc rotatably mounted on said gudgeon pin adjacent that end of the member, and a washer secured to the gudgeon pin to restrain lateral movement of said disc, said disc having a plurality of eccentric slots circumferentially spaced like said arms and into which said pins extend whereby turning of the disc simultaneously protracts or retracts said arms.

4. A bobbin arbor comprising a generally cylindrical body member having a plurality of circumferentially spaced longitudinally extending peripheral grooves, a radially extending arm positioned in each of said grooves, one end of each of said arms being pivoted to the base end of said member and the other end of the arm being capable of radial movement about its pivot, a pin protruding from said other end of each arm, and a disc operatively associated with the other end of said member and adapted to be turned about the longitudinal axis of the member, said disc

5 having a plurality of slots circumferentially spaced like said arms and into which said pins extend, a portion of each of said slots being eccentric and the remaining portion substantially concentric with respect to the longitudinal axis of said member.

10 5. A bobbin arbor comprising a generally cylindrical body member having a hub at one end and a plurality of circumferentially spaced longitudinally extending peripheral grooves, a radially extending arm positioned in each of said grooves, one end of each of said arms being pivoted to said hub and the other end being capable of radial movement about its pivot, a pin extending from said other end of each arm, a pair of spaced washers secured to the end of said body member opposite its hub, a disc positioned between said washers and operatively mounted to turn about the longitudinal axis of the body member, said disc having a plurality of eccentric slots circumferentially spaced like said arms and into which said pins extend whereby turning of the disc simultaneously imparts a similar radial movement to each of said arms.

20 6. A bobbin arbor comprising a generally cylindrical body member having a plurality of circumferentially spaced longitudinally extending peripheral grooves, a radially extending arm positioned in each of said grooves, one end of each of said arms being pivoted to the base end of said member and the other end of the arm being capable of radial movement about its pivot, a pin protruding from said other end of each arm, a gudgeon pin centrally mounted in the other end of said member, a disc rotatably mounted on said gudgeon pin adjacent that end of the member, a washer secured to the gudgeon pin to restrain lateral movement of said disc, said disc having a plurality of eccentric slots circumferentially spaced like said arms and into which said pins extend whereby turning of the disc simultaneously protracts or retracts said arms, a disc covering the base end of said member for limiting lateral movement of a bobbin, and a gudgeon pin centrally mounted in the base end of said member.
